UNITED STATES PATENT OFFICE.

LOUIS V. ARONSON, OF NEWARK, NEW JERSEY.

TALKING-TOY MECHANISM.

1,140,648.

Specification of Letters Patent.

Patented May 25, 1915.

Application filed October 2, 1914. Serial No. 864,583.

To all whom it may concern:

Be it known that I, LOUIS V. ARONSON, a citizen of the United States, and a resident of Newark, in the county of Essex and State of New Jersey, have invented certain new and useful Improvements in Talking-Toy Mechanism, of which the following is a specification.

The invention relates to improvements in so-called talking toys, and more particularly to mechanism for controlling the character of the sound to be emitted thereby.

It has for its object to simplify such mechanism and reduce its cost, as well as to render the said mechanism more positive in its action and less likely to operate unsatisfactorily or become totally inoperative under the rough treatment to which toys of this character are generally subjected.

A further object of the invention is to make the mechanism compact in order that the minimum amount of space will be required for the same in the toys of which it is a part.

The nature of the invention will be best understood when described in connection with the accompanying drawings, in which—

Figure 1 is a plan of the improved mechanism adapted for emitting the desired sounds; and Fig. 2 is a front elevation and Fig. 3 an end elevation thereof. Figs. 4, 5 and 6 are similar views illustrating a modification.

Similar characters of reference designate corresponding parts throughout the several views.

Referring to the drawings, 10 designates a bellows, 11 being the base member thereof and 12 the movable member, the said members being normally held in distended position by means of a spring 13, which may be attached thereto within or without the bellows as is well understood. The bellows is adapted to be suitably secured in position within the body of the toy (not shown) and the movable member actuated by pressing upon some portion of the toy, all of which is well understood and forms no part of the present invention, which has for its object the control of the character and duration of the sound emitted when the said bellows is being compressed. To the upper surface of the movable member 12 of the bellows there is attached the usual reed pipe 14 and which 55 communicates with the interior thereof. One end of the said reed pipe extends into

a sound box 15 which is provided with an orifice 16 permanently open to the atmosphere and with a second orifice 17 normally closed by means of a flap 18, pivotally mounted upon the top of said box 15 and actuated upon by a suitable spring 19. By opening this latter orifice, through the movement of the said flap 18, the character of the sound emitted will be varied, as is well understood; and the duration of such variation as well as the particular succession of the sounds may be controlled to suit the desired toy. To operate the said flap, the same is provided with an arm 20 extending outwardly over the top surface of the movable member 12, although it is to be understood that the flap, as well as its arm and the actuating mechanism therefor hereinafter described, might be placed within the bellows. 75 For convenience, however, it is preferred to place the same as shown. A flat slide or control piece 21, Figs. 1 to 3, having intermediate raised portions or projections 22 and 23, is adapted to rest upon the upper surface of the said member 12; and at one of its ends it is attached by means of a spring 24 to the said member. The other end of the slide 21 is secured to the lower or base member 11 by means of a non-rigid connection such as a cord 25 or the like passing over the end of member 12 and which cord may be suitably guided by a staple 26 or the like attached to the said movable member. The slide 21 is arranged on the member 12 to 80 pass under the arm 20 in order to permit the latter to coöperate with the raised portions 22 and 23 as the slide is moved. Such motion of the slide is obtained when the bellows are compressed, for the slack thus produced in the cord 25 will be taken up by the spring 24 at the other end of the slide, causing the said slide to be drawn in the direction of the said spring, as indicated in dotted lines, Fig. 2. Slide 21, or rather projections 22 and 23 thereof, will thereby engage the arm 20 which is correspondingly raised and effects the desired variation in the character of the sound emitted by opening the flap 18; and the duration of this new tone will depend upon the length of the various projections 22 and 23.

In Figs. 4 to 6, the slide 30, corresponding to the slide 21 hereinbefore set forth, is shown placed vertically with respect to the surface of member 12 and is adapted to ride in a guide groove 31 thereof, the projections

22 and 23 being as hereinbefore described. The said slide, moreover, is similarly under the action of a spring 32 at one end and secured at the other end by means of a cord 33 or the like to the base member 11 of the bellows.

A very simple, compact and effective mechanism is hereby afforded for a positive control of the sound emitted; and, moreover, the same is sufficiently substantial to withstand the usual rough treatment encountered by toys in which such mechanism is employed.

I claim:—

1. Sound controlling device for talking toys, comprising: a reed pipe or the like provided with an orifice, and a suitable bellows carrying said reed pipe and adapted to operate the same; a flap controlling said orifice; an arm extending from said flap; and a slidable member actuated as the bellows is compressed and adapted to coöperate with the said arm to open the flap.

2. Sound controlling device for talking toys, comprising: a reed pipe or the like provided with an orifice, and a suitable bellows carrying said reed pipe and adapted to operate the same; a spring pressed flap normally closing said orifice; an arm extending from said flap; and a slidable member actuated as the bellows is compressed and adapted to coöperate with the said arm to open the flap.

3. Sound controlling device for talking toys, comprising: a reed pipe or the like provided with an orifice, and a suitable bellows carrying said reed pipe and adapted to operate the same; a spring pressed flap normally closing said orifice; an arm extending

from said flap; a spring drawn slide connected at one end to one member of the bellows and at the other end to the other member thereof and adapted to coöperate with the said arm to open the flap.

4. Sound controlling device for talking toys, comprising: a reed pipe or the like provided with an orifice, and a suitable bellows carrying said reed pipe and adapted to operate the same; a spring pressed flap normally closing said orifice; an arm extending from said flap; a spring drawn slide connected at one end to one member of the bellows and at the other end to the other member thereof, said slide being provided with one or more projections adapted to coöperate with the said arm to open the flap.

5. Sound controlling device for talking toys, comprising: a reed pipe or the like provided with an orifice, and a suitable bellows carrying said reed pipe and adapted to operate the same; a spring pressed flap normally closing said orifice; an arm extending from said flap; a slide provided with one or more projections adapted to coöperate with said arm to open the flap; a spring connected to one end of said slide and to the movable member of the bellows; and a non-rigid member connected to the other end of said slide and to the base member of said bellows.

Signed at Newark, in the county of Essex, and State of New Jersey, this 1st day of October, A. D. 1914.

LOUIS V. ARONSON.
